UNITED STATES PATENT OFFICE

ALBERT J. D. OHM, OF OAK PARK, ILLINOIS, ASSIGNOR TO BEARDSLEE CHANDELIER MANUFACTURING COMPANY, OF CHICAGO, ILLINOIS, A CORPORATION OF DELAWARE

DESIGN FOR A LIGHTING FIXTURE

Application filed April 17, 1931. Serial No. 39,519. Term of patent 3½ years.

To all whom it may concern:

Be it known that I, ALBERT J. D. OHM, a citizen of the United States, residing at Oak Park, in the county of Cook and State of Illinois, have invented a new, original, and ornamental Design for Lighting Fixtures, of which the following is a specification, reference being had to the accompanying drawings, which form a part hereof.

My invention, as illustrated, relates to a suspended type of lighting fixture.

In the drawings:

I claim:

The ornamental design for a lighting fixture as shown and described.

ALBERT J. D. OHM.
